BOOT & SHOE COMPANY, OF WORCESTER, MASSACHUSETTS, A CORPORATION OF
MASSACHUSETTS.

HARNESS-STITCHING MACHINE.

Application filed November 10, 1924. Serial No. 748,866.

This invention relates to sewing machines of the type used in stitching shoes, luggage, and other articles formed of leather or of similar material. It is sometimes 5 desirable to produce stitching which will closely resemble hand sewing, such as is found, for instance, in hand made harnesses. This so-called "harness stitch" has been heretofore produced mechanically to a limited 10 extent by impressing or indenting each stitch after it is formed by the sewing machine needle and shuttle. The mechanism provided has been greatly limited in utility, as it would only indent stitches 15 disposed in substantially straight lines and could not be used for indenting stitches for shoemaking or for other purposes where abrupt or short curves abound.

It is the object of my invention to provide 20 a stitching machine by which a harness stitch may be produced mechanically in either straight or curved lines and particularly in curves of very short radius.

To the attainment of this object, a particular 25 feature of my invention relates to the provision of means for swinging the indenting member in one direction or the other to correspond with the curvature of the line of stitching.

Another object of the invention is to provide 30 means by which the feed will be varied as the line of stitching curves to the right or to the left, in such a manner as to provide a substantially uniform stitching and 35 indenting space for either straight or curved stitching.

My invention further relates to arrangements and combinations of parts which will be hereinafter described and more particularly pointed out in the appended claims.

A preferred form of the invention is shown in the drawings, in which—

Fig. 1 is a front elevation of my improved harness stitching machine;

Fig. 2 is a detail plan view, looking in the direction of the arrow 2 in Fig. 1;

Fig. 3 is a detail sectional elevation, taken along the line 3—3 in Fig. 1;

Fig. 4 is an enlarged front elevation of certain parts of the stitching and indenting mechanism;

Fig. 5 is a side view of the stitching and indenting mechanism, looking in the direction of the arrow in Figs. 1 and 4;

Fig. 6 is a detail side elevation, looking 55 in the direction of the arrow 6 in Fig. 4;

Fig. 7 is a detail plan view, looking in the direction of the arrow 7 in Fig. 4;

Fig. 8 is a detail sectional elevation, taken along the line 8—8 in Fig. 4;

Fig. 9 is a sectional side elevation, taken along the line 9—9 in Fig. 4;

Figs. 10 and 11 are partial sectional side elevations, taken along the lines 10—10 and 11—11 in Fig. 1;

Fig. 12 is a plan view of the thread lubricating device;

Fig. 13 is a side elevation thereof partly in section;

Fig. 14 is a detail sectional plan view, 70 taken along the line 14—14 in Fig. 4, and

Fig. 15 shows a sample of the work which may be produced by my improved machine.

Referring to the drawings, I have shown a sewing machine which in many of its 75 features is of a usual commercial type. This machine comprises a frame 20 mounted upon a base 21 suitably secured to a table or other support 22. A needle 23 is clamped in the lower end of a needle bar 24 which is vertically reciprocated by a link 25 pivoted on a crank pin 26 secured at the end of the main driving shaft 27. The shaft 27 extends through the upper portion of the frame 20 and is provided with a 80 pulley 28 which may be driven by a belt 29 from any suitable source of power.

The thread T passes from a suitable guide or support 30 to a lubricating device 31 from which it is guided through an eye 90 32, a friction device 33 and a stitch tensioning device 34 to the needle 23. With the exception of the lubricating device, these parts may be of any usual construction.

The lubricating device is shown in detail in Figs. 12 and 13 and comprises a receptacle 35 for oil or lubricant. The thread enters the top of the receptacle, passing downward through the lubricant to the loop or guide 36, and upward between friction discs 37 and 38, which discs are preferably faced with felt or other cushion ma-

terial and may be adjusted toward or from each other by a screw 39. These friction discs serve to wipe any surplus lubricant from the thread as it is drawn between the discs. The upper disc 38 is preferably provided with an L-shaped slot 40 (Fig. 12) through which the thread is guided.

For producing the effect of a harness stitch, I have provided an indenting device or stitch separator which I will now describe. This indenting device comprises a plunger 45 (Fig. 5) slidable in a bearing bracket 46 which is clamped to the needle bar 24 by a set screw 47 (Fig. 4). A pin 48 (Fig. 5) in the side of the plunger 45 is slidable in a slot 49 in the bracket or bearing 46 and acts to prevent relative angular movement of the plunger in its bearing and also as a stop to limit downward movement thereof.

A coil spring 50 is inserted in the bearing 46 and presses the plunger 45 yielding- 25 down ward to engage the work. The plunger 45 is provided on its lower surface with one or more indenting points 51, which are so spaced relatively to the needle 30 that they will freely enter the needle holes, thus indenting or separating the stitches and producing the effect of hand stitching.

It is a special object of my invention to provide a construction by which the indenting device will accurately enter the needle holes whether the stitching is in straight or sharply curved lines. For this 35 purpose I have provided for angular movement of the needle bar and indenting device about the axis of the needle bar. The mechanism by which this angular movement is produced will now be described.

The needle bar 24 is provided at its upper end with a collar 52 secured thereto and having two grooves 53 (Fig. 14) formed therein. These grooves 53 form 40 guide-ways for a pair of plates or guide-bars 54 mounted on a support 55 (Fig. 6) having an annular groove 56 therein. The support 55 is supported upon an upper arm 57 (Fig. 4) of the frame 20 and is rotatable 45 thereon in a circular recess in a plate 58.

50 Retaining devices 59 extend into the annular groove 56 and prevent displacement of the support 55. The support 55 and guide bars 54 are thus mounted for angular movement about the axis of the needle bar 24 and when thus moved they cause a corresponding angular movement of the needle bar and indenting device, while at the same time the needle bar is freely slidable vertically between the guide-bars 54.

An arm 60 (Fig. 4) is fixed on a rock shaft 61 and is slotted at its outer end as indicated at 62 (Fig. 7) to receive a ball 63 mounted on a stud 64 clamped to a plate 65 secured to the upper end of a post or standard 66 projecting upward from the

angularly movable support 55. As the rock shaft 61 and arm 60 are moved angularly, a corresponding angular movement of the guide-bars 54 will occur.

To permit the angular movement of the 70 needle bar while at the same time maintaining driving connection therewith, I have devised a special connection between the driving link 25 and the needle bar 24. For this purpose I have pivoted the link 25 on a stud 70 projecting laterally from a collar 71 which is loose on the needle bar 24. A member 72 projects upward from the collar 71 and has a yoke 73, the arms of which project into a segmental annular opening or groove 74 in a collar 75 which is secured to the needle bar 24 by a binding screw 76. The collar 71 is thus connected to reciprocate the needle bar while at the same time a considerable range of relative angular 80 movement is permitted.

The rock shaft 61 is provided with an arm 80 (Fig. 11) having a ball and socket connection 81 to a connecting rod 82. The lower end of the rod 82 (Fig. 1) has a similar connection to an arm 83 (Figs. 1 and 2) mounted on a control shaft 84 which is supported in bearings 85 on the table 22. An arm 86 projects downward from the shaft 84 and supports a cross bar 87. Collars 88 are adjustably secured to the cross bar 87 and are provided with depending rods 89 on which knee pads 90 are adjustably secured. By pressing upon one or the other of the knee pads 90, the shaft 84 will be rocked in a corresponding direction and this will in turn cause similar angular movement of the rock shaft 61 and the needle bar 24.

It is desirable that the rock shaft and 105 needle bar be yieldingly maintained in normal position when there is no pressure upon the knee pads. For this purpose I provide arms 91 and 92 (Fig. 2) engaged by compression springs 93 and thus yieldingly 110 restored to the position shown in Fig. 2, after manual displacement in either direction.

As a further means for holding the rock 115 shaft 66 yieldingly in normal position, I have provided a cam plate 95 (Fig. 9) having a flat surface 96, engaged by a block 97 mounted on a spring arm 98 secured to a fixed portion of the machine frame 20. A flat spring 99 is also secured to the frame 20 and carries an adjusting screw 100 by which increased pressure may be applied to the block 96. If the rock shaft 61 is turned angularly in either direction, the cam 95 will force the block 97 outward and the pressure of the spring plate 98 and 99 will act to restore the cam 95 and shaft 61 to normal position, whenever the manual pressure on the knee pads is removed.

The shuttle 101 (Fig. 5) is substantially 120

of the usual oscillating type, except that certain of the parts are made right hand instead of left hand.

By the mechanism thus far described, I am able to swing the needle bar and indenting device angularly at the will of the operator so that the indenting device will be aligned with the needle holes when the machine is stitching short curves, such as are indicated in Fig. 15. In this way the indentations are formed exactly in the needle openings instead of being thrown out of line, a condition which occurs when the needle bar and indenting device are fixed in angular position.

This feature of my invention is of great value and is essential to the production of an efficient harness stitching machine to be used on curved lines of stitching.

I have found, moreover, that the length of the stitch is not constant when stitching around short curves. If the curvature is in one direction, the stitches are much closer together, and if the curvature is in the opposite direction, the stitches are much further apart. For satisfactory work, it is necessary that all of the stitches be substantially equal in spacing and accordingly I have provided mechanism for increasing or decreasing the feed in accordance with the direction of curvature, so that the above described variation in spacing may be counteracted and a substantially uniform spacing will result.

For this purpose, I have provided the rock shaft 61 with an additional arm 105 (Fig. 10) supporting a rod 106 having a ball and socket connection with a link 107, similarly connected to a bell crank lever 108, mounted on a fixed pivot 109, and connected by a link 110 to the usual feed fork 111. By these connections the feed fork will be raised or lowered as the rock shaft 61 is moved angularly in one direction or the other. This vertical adjustment of the feed fork causes an increase or decrease in the feed in the usual manner through well known connections not shown in the drawings.

With this additional attachment, I am able not only to keep my indenting or separating device in line with the needle openings but I can also counteract the variations in spacing which otherwise occur in stitching around short curves and I am thus able to produce harness stitching either in straight or curved lines with the stitches substantially uniformly spaced and equally indented. The resulting product is ornamental and very satisfactory and this machine enables me to produce harness stitching on shoe caps and uppers and on many other articles for which it has not heretofore been available.

Having thus described my invention and the advantages thereof, I do not wish to be limited to the details herein disclosed other-

wise than as set forth in the claims, but what I do claim is:—

1. A harness stitching machine, comprising a frame, a needle bar mounted to reciprocate therein, a stitch separating device, mounted to reciprocate with said needle bar, and controlling means to move said separating device transversely to its path of reciprocation. 70

2. A harness stitching machine, comprising a frame, a needle bar mounted to reciprocate therein, a stitch separating device and means to move said stitch separating device angularly about the axis of said needle bar. 75

3. A harness stitching machine, comprising a frame, a needle bar mounted to reciprocate therein, a stitch separating device, and means to move said needle bar and separating device angularly about the axis 85 of said needle bar.

4. A harness stitching machine, comprising a frame, a needle bar mounted to reciprocate therein, a stitch separating device acting upon the stitches after formation by the needle and means to move said stitch separating device angularly about the axis 90 of said needle bar.

5. A harness stitching machine, comprising a frame, a needle bar mounted to reciprocate therein, a stitch separating device, and means controlled by the operator effective to change the relative angular position of said bar and device in respect to said frame. 95

6. A harness stitching machine comprising a frame, a needle bar mounted to reciprocate therein, a stitch separating device, and means controlled by the operator effective to move said separating device 105 angularly in either selected direction about the needle bar.

7. A harness stitching machine comprising a frame, a needle bar mounted to reciprocate therein, a stitch separating device, means controlled by the operator effective to move said separating device about its support, and means to yieldingly restore said separating device to its normal position when said controlled means is released. 110

8. A harness stitching machine comprising a frame, a work feeding mechanism, a stitch-forming mechanism, a stitch separating device, and means to simultaneously 120 change the relative position of said separating device in respect to said frame and to vary the action of the feeding mechanism.

9. A harness stitching machine comprising a frame, a work feeding mechanism, a stitch-forming mechanism, a stitch separating device, means to move said separating device angularly about its support and to increase the feed as said device is moved 125 angularly in one direction. 130

10. A harness stitching machine comprising a frame, a work feeding mechanism, a stitch-forming mechanism, a stitch-separating device, means to move said separating device angularly about its support and to decrease the feed as said device is moved angularly in one direction.
11. A harness stitching machine comprising a frame, a work feeding mechanism, a stitch-forming mechanism, a stitch-separating device, means to move said separating device angularly about its support and to increase the feed as said device is moved angularly in one direction and to decrease the feed as said device is moved angularly in the opposite direction.
12. A harness stitching machine, comprising a frame, a needle bar mounted to reciprocate therein, a stitch separating device mounted to reciprocate with said needle bar, and controlling means to move said separating device transversely to its path of reciprocation, said controlling means including a rock shaft, a cam plate fixed thereto, and a spring plate yieldingly engaging a flat face on said cam plate to restore said shaft to normal position.
13. A harness stitching machine comprising a frame, a needle bar mounted to reciprocate therein, a stitch separating device mounted to reciprocate with said needle bar, and controlling means to move said separating device transversely to its path of reciprocation; said controlling means including a rock shaft and a pair of opposed springs acting to yieldingly restore said shaft to substantially normal position.
14. In a sewing machine, angularly adjustable stitching mechanism, feeding mechanism adjustable therewith, including manual control means to vary the length of the feed in accordance with changes in the amount and direction of curvature of the line of stitching.
15. In a sewing machine, angularly adjustable stitching mechanism, feeding mechanism, and means to increase the length of the feed as the stitching curves in one direction and to decrease the length of the feed as the stitching curves in the opposite direction.

In testimony whereof I have hereunto affixed my signature.

MALCOLM G. BLISS.
